SAFETY HOLDER FOR EARRINGS

Olaf H. Thronsen, New York, N. Y.

Application December 29, 1945, Serial No. 638,219

2 Claims. (Cl. 63—14)

1

This invention relates to a new and novel type of safety holder for earrings or ear ornaments, more particularly, it relates to a holder for earrings permitting secure attachment of earrings or similar ear ornaments insuring the owner against loss of the earrings once applied.

The device of the new invention is extremely simple in construction and very simple in operation. It can readily be made from well known, economical and available material. In spite of its many advantages it would not in any way detract from the attractiveness of an ear ornament and would not increase the discomfort of the wearer.

Far from this, it will actually completely eliminate the need for perforating the ear lobe permitting a wide number of persons heretofore unable to wear ear ornaments, the enjoyment of this attractive accessory. In contrast to perforation of the ear lobes the new device is entirely safe in application and extremely hygienic as well as highly conserving of ear ornaments.

For further comprehension of the invention, and of the objects and advantages thereof, reference will be had to the following description and accompanying drawings, and to the appended claims in which the various novel features of the invention are more particularly set forth.

In the attached drawings forming an important part of the specification where similar parts are denoted as similar numerals:

Fig. 1 is a front view illustrating an ear ornament attached to the product of the instant invention.

Fig. 2 is a side view illustrating the device of the preceding figure.

Fig. 3 is a side view illustrating attachment device apart from the ear ornament.

Fig. 4 is a front view illustrating another embodiment of the invention.

Fig. 5 is a side view of the embodiment shown in Fig. 4.

Fig. 6 is a horizontal section through line 6—6 of Fig. 4.

In accordance with the invention, an ear ornament 10 is attached to a holder 11 having a conventional clamp 12 fit to a clamp around an ear lobe to which it may be tightly attached by means of set screw 13. In a direction opposite to said clamp 12 there extends from holder 11 a piece of narrow resilient wire 14 which ends in a narrow bent 15 extending into a stiffened extension plate 16 which may be in the shape of a little round ball.

The entire attachment 11 is so formed as to

2

permit insertion of extension plate 16 into the natural hollow just above the ear lobe when screw 13 is set so as to tightly attach ornament 10 to the ear lobe itself.

5 The operation of this embodiment which is illustrated in Figs. 1-3 of the invention is as follows:

An ornament 10 is soldered or otherwise attached to attachment 11. The attachment is 10 then fitted on an ear lobe by putting clamp 12 around the lower limit of the ear lobe and inserting disc 16 into the round opening just above the ear lobe. After set screw 13 has been regulated so as to tightly attach clamp 12 around the ear lobe, a secure hold of the ornament on the ear has been obtained.

In another embodiment of the invention shown in Figs. 4-6, the same type of clamp 12 and set screw 13 is utilized. However, this time a plurality of resilient wires 15' replace resilient wire 15 of the preceding embodiment. The two outermost resilient wires 15' have little teeth near the point where they extend from the body of attachment 11. These teeth 17 extend in each case 15 in an outward direction as shown. A small staple like clamp 18 can be moved along wires 15' hooking into teeth 17 as desired. This will lock the wires 15' in any desired relation to each other.

In the operation of the device of Figs. 4-6 the attachment is fitted around the ear lobe as in the preceding device but individual extensions 15' are adjusted so as to fit the interior outline of the particular ear of the wearer when disc 16' is inserted as desired. Staple like clamp 18 is now moved along the wires 15' and teeth 17 so as to securely lock them into position.

From the above description, it will be readily seen that a device has been created permitting secure attachment of ornaments of all types to the human ear and particularly to the ear lobe. The danger of losing an ear ornament while wearing it is substantially less where one uses the present invention.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In an earring including a lobe clamp mounting an ornament, a safety attachment compris-

ing, a pair of resilient extensions formed integrally with the lobe clamp and projecting in spaced relationship from the lobe clamp, said extensions terminating in arcuate portions, the extremity of each arcuate portion mounting a globular disc adapted to engage in the hollow of the human ear above the lobe, and means for adjusting the spaced relationship of the resilient extensions.

2. An earring comprising, a substantially 10 U-shaped lobe clamp provided with a set screw operating transverse the open end thereof, an ornament secured on one leg of the clamp, that end of said leg beyond said ornament being divided to form a part of spaced resilient extensions, the extremity of each of said extensions terminating in an arcuate portion, a globular disc supported at the extreme end of each arcuate extension portion adapted to engage in the natural hollow of the ear above the lobe, teeth 15 20

formed along each of said extensions adjacent their juncture at the clamp, and a staple-like clamp disposed between and having selectively locking engagement with the teeth of said extensions.

5
